ELECTRIC CLOCK MECHANISM

Ralph Magro, Jersey City, N. J., assignor, by
mesne assignments, to Joseph Lipack and
George Yamin, Bayonne, N. J.

Application October 28, 1933, Serial No. 695,699

3 Claims. (Cl. 58—38)

My present invention relates to time mechanism and more particularly to an improved electrically driven time indicating instrument.

5 My invention also relates to improved time striking mechanism.

Pursuant to my present invention, I provide a mechanism which produces the desired time indication by utilization of minute and hour hands, and also a second hand if desired, all of which are driven at appropriate speeds by a synchronous motor and with a step by step movement having visually substantially the characteristic of continuous movement of the minute hand.

10 Further I have devised a striking mechanism for such and other time keeping instruments and which is operated at appropriate times by the timing train.

In carrying out my invention I preferably associate with a shaft driven at a constant speed as 15 by a synchronous electric or other suitable motor, a ratchet and pawl mechanism which is associated with a shaft carrying, if desired, a second hand, and which ratchet and pawl mechanism operates once for each second interval of time to 20 produce an intermittent rotary motion of the shaft corresponding to or carrying the seconds hand and which therefore will impart a step by step rotary movement to the seconds hand about its axis of rotation. Further, I associate with 25 the seconds shaft, as above described, a cam which in turn controls a pawl that intermittently rotates a shaft carrying a minute hand.

30 While I may carry such construction to the point where the hour hand is also moved step-by-step, I prefer to associate with the shaft carrying the minute hand a pinion which meshes with and drives a shaft carrying the hour hand and accordingly the hour hand is driven at a pre-determined constant speed with relation to the 35 speed of travel of the minute and seconds hands.

With the mechanism, as for example the shaft carrying the hour hand, I associate a cam or equivalent mechanism for determining the duration of operation of a striking mechanism and this striking mechanism is provided with means for periodically striking a bell, conveniently once 40 per second, the proper number in accordance with the hour or other time indication.

An object of my invention therefore is an improved time keeping mechanism.

An object of my invention is a preferred time keeping mechanism operated by a synchronous motor.

45 A further object of my invention is an improved time keeping mechanism wherein the time indi-

cating elements are intermittently driven step by step at a predetermined rate of speed by a synchronous motor.

An object of my invention is a striking mechanism for synchronous motor driven time keeping mechanisms.

An object of my invention is an improved striking mechanism controlled by a synchronous or other suitable motor driven time keeping mechanism.

Other objects and features of the construction comprised in my device will appear as the description of the invention progresses.

In the accompanying drawings.

Fig. 1 is a vertical sectional elevation through a time keeping mechanism embodying my invention;

Fig. 2 is a sectional elevation on the line 2—2 of Fig. 1;

Fig. 3 is a sectional side elevation on the line 3—3 of Fig. 1 and showing the striking operation mechanism in one position;

Fig. 4 is a view similar to Fig. 3 and showing the striking operation mechanism in another position;

Fig. 5 is a fragmentary plan view on the line 5—5 of Fig. 3, and

Fig. 6 is a circuit diagram of the electrical connections of my improved device.

Referring to the drawings, 10 designates a casing usually and preferably of wood within which is located the mechanism of the time keeping device and time striking mechanism, this casing 10 being closed at the front end by a closure member 11 and at its rear end by a metallic cover 12, which may be secured to the casing 10 by the screws 13. Secured to the rear face of the front closure member 11, by screws 14, are brackets 15 and to these brackets are secured, as by nuts 16, the posts 17. Between the nuts 16 and the brackets 15 is positioned a bearing plate 18. The space between the front face of the plate 18 and the rear face of the front closure member 11 provides a housing for the purpose to be hereinafter described.

Secured to the posts 17, as at the end thereof remote from the brackets 15, is a bearing plate 19, this plate being spaced apart from and lying parallel to the bearing plate 18, and secured in position on the post 17 by the nuts 20.

The front closure member 11 is provided with a centrally arranged orifice 21 and with a countersunk portion 22 on its outer face, for a regulation or other dial plate 23, which may be held in position by a bezel ring 24 carrying a sight or

crystal 25. Centrally arranged in the bearing plate 18 is a bearing 25a and in which is rotatably mounted a sleeve 26. This sleeve at its outer end passes through a centrally arranged perforation in the dial plate 23, which perforation also acts as a bearing, and secured to the outer end of the sleeve 26 is a bushing 27 carrying the hour hand 28.

Secured to the rear end of the bushing 26, as by staking or in any other desired manner, is a gear 29 which meshes with and is driven by a pinion 30, rotatably mounted on a stud shaft 31, suitably secured to the rear face of the bearing plate 18, as by riveting. Secured to the rear face of the pinion 30 is a gear 32, the gear 32 and pinion 30 being held in position on the stud shaft 31 by the screw 33. The gear 32 meshes with and is driven by a pinion 34, suitably secured to the rear end of a sleeve 35, which sleeve 20 is slidably and rotatably mounted in the bushing 26. Such sleeve 35 at its outer end has secured thereto the minute hand 36.

Secured to the pinion 34, by staking or in any other desired manner, is a ratchet 37 which is adapted to be engaged by a driving and locking pawl mechanism comprising an arm 38 pivotally mounted on one of the posts 17, and the free end of this arm extends radially outward from the axis of the particular post 17 employed. The free end of the arm 38 extends to a point slightly beyond the axis of the tubular member or sleeve 35. Secured to the arm 38, by screw 39, is a spring driving pawl 40 which engages with the teeth of the ratchet wheel 37. Secured to the arm 38 by screw 41 is a spring holding pawl 42 which likewise engages with the teeth of the ratchet wheel 37. Extending through the sleeve 35 and rotatably mounted therein is a shaft 43, and the rear end of this shaft is reduced in diameter, as indicated at 44, and cooperates with a bearing in the rear bearing plate 19.

The outer, or front end, of the shaft 43 may have attached thereto a seconds hand 45.

The shaft 43 has secured thereto, as by pin 46, a sleeve 47 to which is attached a cam 48, this cam engaging with the extension of the arm 38. Secured to the sleeve 47 is a ratchet wheel 49, which is similar to the ratchet wheel 37 above described, and such ratchet wheel 49 is shown in front elevation in Fig. 2. With the ratchet wheel 49 coacts a spring driving pawl 50 and a spring holding pawl 51. The pawls 50 and 51 are carried by an arm 52, similar to the arm 38, and which is rotatably mounted on one of the posts 55 17 and has an extension 57 which projects slightly beyond the axis of the shaft 43. The spring driving pawl 50 is attached to the arm 52 by screw 53, while the spring holding pawl 51 is attached to the arm 52 by the screw 54.

Rotatably mounted on the shaft 43 is a sleeve 55, and to such sleeve is secured a cam 56. This cam 56 is adapted to engage with the extension 57 of the arm 52 and imparts an oscillatory motion thereto, thus imparting an oscillatory motion to the spring driving pawl 50, and thus producing an intermittent or step-by-step rotation of the sleeve 49.

Secured to the sleeve 55 is a gear 58 which meshes with and is driven by a pinion 59 secured to a shaft 60, such shaft 60 being rotatably mounted in a bearing 61, secured to the rear bearing plate 19 and in a bearing 62 secured to a bracket 63, attached to the rear face of the bearing plate 19. The shaft 60 extends rearwardly of the device or to the left as shown in Fig. 1,

and has attached to its rear end a knob 64 located outside of the cover plate 12, and by means of which the shaft 60 may be manually rotated. To the shaft 60, between the bearings 61 and 62, is secured a rotor 65 cooperating with pole pieces 66 of a synchronous motor, such pole pieces being attached to the upper posts 17 and adjacent the rear bearing plate 19. The two pole pieces 66 at their upper ends are joined by a bar 67 and mounted on such bar is an energizing coil 68. The effective peripheral notches of the pole pieces and of the rotor may be varied to control the rate of rotation of the rotor.

Suitably mounted, as on the front face of front bearing plate 18 in any convenient position, i. e., at the lower right hand corner thereof as viewed in Figs. 3 and 4, is a terminal block 69 of any desired insulating material. This terminal block 69 is provided with terminals 70, 71, 72 and 73, although the number of such terminals is immaterial and as many terminals may be provided as is necessary to insure proper connection and wiring for as many circuits as may be desirable. Conductor 74 of a main feed supply is shown connected to the terminal 70 and a conductor 75 from the main feed supply is shown connected to the terminal 73. From the terminal 70 leads a conductor 76 which is attached to one end of the coil 68 while leading from the terminal 73 is a conductor 77 attached to the other end of the coil 68. The coil 68 is therefore always supplied with current from the conductors 76 and 75 connected to the main feed supply and power is thus assured to cause synchronous rotation of the rotor 65 with respect to the character of the current. The rotor 65 is attached to the shaft 60, adjacent to the bearing 62, and also mounted on the shaft 60 in close association with the rotor 65 is a disk 78, such disk being freely rotatable on the shaft 60. On the shaft 60 and adjacent to bearing 61 is provided a fixed collar 79 and between the fixed collar 79 and the rotatably mounted plate 78 is a spring 80 which normally holds the plate 78 in frictional engagement with the rotor 65 but which allows relative movement therewith. Although the synchronous motor composed of the elements 65, 66, 67 and 68 may be self-starting, I find it desirable to provide the knob 64 for manually rotating the shaft 60, and therewith the rotor 65, to start the rotor 65 in motion preparatory to having the rotary movement continue under the actuation and control of the current passing through the coil 68.

As thus far described, it is obvious that with my invention, while power is transmitted to the seconds, minute and hour hands 45, 36 and 28 respectively, from the synchronous motor, such power operates the seconds and minute drives with an intermittent step-by-step movement rather than a continuous movement. For example, the rotor 65 imparts a continuous rotary movement to the pinion 59 and at an assumed speed of 120 revolutions a minute. The rotary movement of the pinion 59 is imparted to the gear 58 on the collar 55 which thus also is rotated continuously but at a speed equal to 60 revolutions a minute, the ratio between the pinion 59 and the gear 58 being designed for such speed reduction. Therefore, the cam 56 is also rotated continuously and at a rate of speed equal to 60 revolutions a minute. The cam 56 therefore engages with the arm 57 and imparts an oscillatory motion thereto once per second and therefore the spring driving pawl 50 rotates the ratchet 49 in the direction of the applied arrows, see Fig. 2, 75

the distance of one tooth every second and as there are 60 teeth in the ratchet wheel 49 such ratchet wheel 49 makes one complete revolution every minute, and therefore the second hand 45 makes one complete revolution every minute. As the ratchet wheel 49 is carried by the sleeve 47, which in turn is pinned to the shaft 43, and as the sleeve 47 also carries a cam 48, the cam 48 makes one complete revolution every minute and therefore the cam 48, engaging with the arm 38, such arm 38 imparts thereto an oscillatory movement once every minute, and by means of its driving spring pawl 40 imparts a step-by-step rotary movement to the ratchet wheel 37, one stroke per minute. The ratchet wheel 37, being provided with 60 teeth, such ratchet wheel makes a complete revolution every hour, or 60 minutes, thereby imparting a complete revolution once per hour to the minute hand 36. The hour hand 28 being geared directly to the pinion 34 on which the ratchet wheel 37 is mounted imparts thereto a continuous rotary movement and makes one complete revolution every twelve hours.

In addition to the time keeping mechanism as above described I have associated therewith a time striking mechanism such as is illustrated in Figs. 3, 4, 5 and 6. Referring to such figures and also to Fig. 1, there is shown attached to the front face of the front bearing plate 18 and in the rear of the closure member 11 a stud shaft 81 on which is pivotally mounted an arm 82, provided at its free end with a ratchet quadrant 83. Also on the arm 82, intermediate its ends, and extending laterally therefrom is a pin 84, which pin 35 is adapted to cooperate with a stepped cam member 85, secured to the sleeve 35 that carries the hour hand 28. The stepped cam 85 is provided with a series of twelve steps as shown in Figs. 3 and 4, each step representing a predetermined interval, conveniently of an hour's time, and which limit the downward rotary movement of the arm 82 and therefore limit the downward movement of the ratchet quadrant 83. Secured to the bearing plate 18, by screw 86, is a spring holding pawl 87 which engages with the teeth of the ratchet quadrant 83 and holds the same in its uppermost position except under certain conditions to be hereinafter specified. The screw 86 may also secure in position a spring member 88, 50 which spring member extends upwardly and to the right, as viewed in Figs. 3 and 4, and at its outer free end engages with a hollow switch member 89. Such switch member 89 is held in a clip 90 that is pivotally attached to the bearing plate 18 by screw 91. Located and sealed within the closed member 89 are contacts, one of which, say, the contact 92, is connected by conductor 93 to the terminal 70 and the other, i. e., contact 94, is connected by conductor 95 to the terminal 71. 55 The contacts 92 and 94 are out of engagement with each other and are electrically connected by a liquid conducting material 96 such as mercury, located within the member 89. Referring to Fig. 3, it is noted that the liquid conducting material 96 is at the end of the member 89 remote from the contacts 92 and 94 and therefore the circuit between the contacts 93 and 95 is broken at the contacts 92 and 94 for such position. Referring to Fig. 4 it will be noted that the liquid conducting material 96, because of the position of the member 89 on the pivot screw 91, is at the end of the member 89 containing the contacts 92 and 94 and the liquid conducting material electrically connects the contacts 92 and 94 in such

position, thus completing the circuit between the conductors 93 and 95.

As an exemplification of one means for rotating the arm 82 about the stud shaft 81, I provide a shaft 97, rotatably mounted in bearings in the bearing plates 18 and 19, and on such shaft secure in any convenient manner an arm 98. To the outer free end of the arm 98, I secure, as by screw 99, a spring driving pawl 100 which normally engages with the teeth in the ratchet quadrant 10 83. Also, on the shaft 97, I secure an arm 101 which extends forwardly, i. e., to the right as shown in Figs. 3 and 4, and into a position to be engaged by the cam 56 that is secured to the sleeve 55. 15

Assuming that Fig. 4 shows in normal position the arm 82 which carries the ratchet quadrant 83 and that the rotor 65 is rotated, under such conditions for each revolution of the cam 56 there is an oscillatory movement imparted to the arm 20 101. This in turn imparts a step-by-step movement to the ratchet quadrant 83, thus moving the same step-by-step from the position shown in Fig. 4 to the position shown in Fig. 3. Each forward step of the ratchet quadrant 83 caused by 25 the movement of the spring driving pawl 100, is maintained by the spring holding pawl 87 so that in the uppermost position of the ratchet quadrant 83 as shown in Fig. 3, such arm 82 and ratchet quadrant 83 is maintained as shown regardless of the subsequent oscillatory movement 30 imparted to the spring driving pawl 100. It will be noted that below the ratchet teeth on the ratchet quadrant 83 there is formed a flat surface 102 on which the spring driving pawl 100 35 slides in subsequent movement of the same and this condition is maintained until mechanism to be hereinafter described operates to release the ratchet quadrant 83.

In bearings in the bearing plates 18 and 19 40 and below the shaft 97 is rotatably mounted a shaft 103, and secured to such shaft and extending radially outward therefrom is a bar or pin 104. This bar or pin 104 lies in the path of movement of a pin 105 secured to and extending outward from one face of the ratchet wheel 37, which ratchet wheel makes one complete revolution every hour. Secured to one end of the shaft 103 is a modified bell crank lever, one arm 106 of which is curved as shown in Figs. 3 and 4 and is 45 adapted to engage with the spring member 88 to thus cause a rotary movement of the member 89 about the pivot screw 91 to move the member 89 from the position shown in Fig. 3 to the position shown in Fig. 4. Also this arm 106 engages with 50 an arm 107 formed integral with and extending laterally outward from the spring driving pawl 100, so that simultaneously with the rotary movement imparted to the member 89, the driving pawl 100 is moved out of engagement with the 55 ratchet quadrant 83. Also, as the spring holding pawl 87 is formed integral with the spring member 88, such holding pawl 87 is released at this time from the ratchet quadrant 83, which thereupon is permitted to fall from the position shown 60 in Fig. 3 into the position shown in Fig. 4 or into any intermediate position depending upon the particular step of the stepped cam 85 that is in position under the pin 84 on the arm 82. The other arm 108 of the said modified bell crank 65 lever is provided with clips 109 in which is mounted a hollow switch member 110. This hollow switch member 110 is quite similar to the hollow switch member 89, and has sealed therein at one end a pair of contacts one of which, as the 70 75

contact 111, is connected by conductor 112 to the terminal 72 on the terminal block 69 and the other contact, i. e., 113, is connected by conductor 114 to the terminal 73. Within the hollow switch member 89 is placed a sufficient quantity of liquid conducting material 96 which is normally in position to engage with the contacts 111 and 113 as shown in Fig. 3, but which on the rotation of the modified bell crank lever is moved out of engagement therewith as shown in Fig. 4. Secured to the bearing plate 18 is a pin 116 which limits the rotary movement (in one direction) of the modified bell crank lever.

Suitably mounted on the base 10 as by screws 117, is a bracket 118 and on this bracket is mounted a solenoid 119. Secured to the upper end of the solenoid 119 is a bell 120 and slidably mounted in the solenoid is a plunger armature 121, carrying at the upper end a slidably mounted rod 122. Secured to the lower end of the plunger armature 121, as by screws 123, is an operating arm 124 which extends radially outward, and then upward, and at its upper free end has pivotally attached thereto a clapper operating rod 125. This rod passes through an eye 126, see Fig. 1, formed in the upper end of the rod 122 and is provided with a ball 127 which engages with the bell 120. One end of the solenoid 119 is connected by conductor 128 to the terminal 71 while the other end of such solenoid is connected by conductor 129 to the terminal 72, see Fig. 6. Therefore, upon the hollow switch member 89 being in its position shown in Fig. 4 and hollow switch member 110 in the position shown in Fig. 3, the circuit is completed, see Fig. 6, from the conductor 74, terminal 70, conductor 93, contacts 92 and 94, conductor 95, terminal 71, conductor 128, solenoid 119, conductor 129, terminal 72, conductor 112, contacts 111, 113, conductor 114, terminal 73 and conductor 75 and the solenoid 119 is energized to attract its plunger armature 121, and therewith the ball 127 strikes the bell 120.

Assuming the time mechanism above described to be in operation so as to bring the stepped cam 85 gradually into its position shown in Figs. 3 and 4 and that such position indicates twelve o'clock, the pin 105 engages with the arm 104 to rotate the shaft 103 in a counter-clockwise direction and brings the bell crank arm 106 into engagement with the spring member 88 and the arm 107 on the driving pawl 100, thus moving the hollow switch member 89 from its position shown in Fig. 3 into its position shown in Fig. 4, thereby effecting the liquid conducting material 96 to bridge the gap between the conductors 92 and 94 and release the holding pawl 87 and driving pawl 100 from the teeth on the ratchet quadrant 83. The ratchet quadrant 83 then falls from the position shown in Fig. 3 to the position shown in Fig. 4.

As, however, it is not desirable to have the bell 120 strike before a complete sequence of bell striking operations may take place, and it is not desired to have the closing of the circuit between the contacts 92 and 94 cause an energization of the solenoid 119 at this time, such striking does not take place due to the fact that the moving of the hollow switch member 89 into its position shown in Fig. 4 can only take place because of the further rotary movement of the shaft 103. The rotary movement of the shaft 103, in addition to moving the hollow switch member 89 to its position shown in Fig. 4, also moves the member 110 as to cause the flow of its liquid con-

ducting material 96 from the contacts 111 and 113 to the other end of the member 110, i. e., into its circuit opening position shown in Fig. 4. Therefore, no striking of the bell 120 as yet takes place.

The release of the driving pawl 100 and the holding pawl 87 permits the ratchet segment 83 to fall from its position shown in Fig. 3 to its position shown in Fig. 4, the amount of downward movement of such quadrant, as above explained, being limited by the amount of downward movement permitted by particular step of the stepped quadrant 85 located immediately beneath the pin 84 on the arm 82.

As above assumed, that in the position of the mechanism shown in the drawings is of twelve o'clock, immediately upon the pin 105 moving off the end of the rod 104, shown in Fig. 4, the bell crank lever arm 106 which carries the hollow switch member 110, is permitted to return to its original position, i. e., as shown in Fig. 3, the liquid conducting material 96 moves into engagement with and completes the circuit between contacts 111 and 113.

As, however, the return of the bell crank lever to its normal position, i. e., as shown in Fig. 3, permits the holding pawl 87 and the spring member 88 to move into their normal positions, the hollow switch member 89 moves into its position shown in Fig. 3, thus shifting the liquid conducting material 96 to break the electrical circuit between the contacts 92 and 94. As the timing mechanism operates, the cam 85 rotates the arm 101 about its axis 97, thus operating the spring driving pawl 100 which moves the ratchet quadrant 83 upward the distance of one step. In such movement the holding pawl 87 rides over the top of the tooth on the ratchet quadrant 83 with which it is in engagement, thus lifting the member 88 to its uppermost position or into substantially the position shown in Fig. 4, again rotating the hollow switch member 89 so as to shift its liquid conducting material 96 into position to bridge the circuit between the contacts 92 and 94, and complete the energizing circuit of the solenoid 119 with the power conductors 74 and 75, through the hollow switch members 89 and 110 in series.

At the end of the stroke of the spring driving pawl 100 the holding pawl 87 drops in behind the tooth over which it has just ridden, holding the ratchet quadrant 83 in its upward position, and permitting the member 88 to move into the position shown in Fig. 3, thus permitting the hollow switch member 89 to rotate and move the liquid conducting material 96 from out of engagement with the contacts 92 and 94, thus open-circuiting at such contacts the energizing circuit of the solenoid 119 and permitting the ball 127 to drop into engagement with the bell 120 and strike one blow.

The next cycle of operation as above described takes place one second later and therefore the bell 120 is operated one blow each second until the desired number of strikes, in the assumed instance, a series of twelve strikes, after which, as the driving pawl 100 slides idly on the surface 102 there is no longer imparted to the curved spring member 88 any upward and downward movement and therefore the hollow switch member 89 remains in its open-circuit position shown in Fig. 3. The stepped cam 85 therefore is free to rotate as the pin 84 on the arm 82 is out of its path of travel and the above cycle of operations is repeated one hour later, when in the assumed in-

stance, the step representing one o'clock is brought into vertical alignment with respect to the movement of the pin 84.

It will thus be seen that I have devised not only a time keeping motor driven mechanism of novel and advantageous design but have also associated therewith a time striking mechanism which utilizes the same source of energy as the actuating medium for the time mechanism and which exerts no disturbing effect upon the time accuracy qualities of the time keeping mechanism.

Whereas I have described my invention by reference to specific forms thereof, it will be understood that many changes and modifications may be made without departing from the spirit of the invention.

I claim:

1. A striking mechanism for time keeping devices having in combination, a rotatably mounted stepped cam, a pivoted arm provided with means for engaging with the steps of the cam, a ratchet quadrant carried by said arm, means for releasing said ratchet quadrant from its normal position to a position determined by the engagement of the means associated therewith with the cam, a second means for moving said ratchet quadrant back to its normal position, a time striking device, an energizing circuit therefor including a pair of break points, one of said break points being controlled by the first said means, and means controlled by the ratchet quadrant during its return movement and controlling the other break point in the energizing circuit to operate the time striking device.

2. A striking mechanism for time keeping devices having in combination, a stepped cam, a pivoted arm provided with means for engaging

with the steps of the cam, a ratchet quadrant carried by said arm, means for releasing said ratchet from its normal position to a position determined by the engagement of the means associated therewith with the cam, a second means intermittently moving said ratchet quadrant back to its normal position, a time striking device, an energizing circuit therefor including a pair of break points, one of said break points being normally held in closed position by the first said means, and means controlled by the ratchet quadrant during its return movement and intermittently controlling the other break point in the energizing circuit to operate the time striking device.

3. A striking mechanism for time keeping devices having in combination, a stepped cam, a pivoted arm provided with a pin for engaging with the steps of the cam, a ratchet quadrant carried by said arm, means for releasing said ratchet quadrant from its normal position to a position determined by the engagement of the said pin with the stepped cam, a second means intermittently moving said ratchet quadrant back to its normal position, a time striking device, an energizing circuit therefor including a pair of break points, one of said break points being normally held in closed position by the first said means, and means controlled by the ratchet quadrant during its return movement and intermittently operating the other break point in the energizing circuit to operate the time striking device, the means for releasing the ratchet quadrant from its normal position maintaining the break point controlled thereby in the energizing circuit open during its releasing operation and until its return to initial position.

RALPH MAGRO.
